UNITED STATES PATENT OFFICE.

GEORGES ERNEST WAGNER, OF ST.-ETIENNE, FRANCE.

BALANCED ROTARY PERCUSSION IMPLEMENT.

Application filed May 13, 1926, Serial No. 108,931, and in France January 16, 1926.

My invention relates to a rotary percussion implement or apparatus in which the construction is such that the parts in motion will be constantly balanced.

5 It is a known fact that in rotary percussion implements, there are employed a certain number of striking or impact bodies, and usually an even number, which rotate at high speed and follow the internal profile 10 of the main casing, the said bodies striking, through the intermediary of a tool holder, upon a tool in contact with the piece of work.

In my invention, the internal outline of 15 the casing is such that all points of the trajectory of the striking bodies are symmetrical in pairs, except in the part adjacent to the tool holder, in which the symmetry is only approximate.

20 A constructional form of percussion implement which is balanced in accordance with my said invention is shown in the appended drawings.

Fig. 1 is a section through the middle 25 part of the implement.

Fig. 2 is a section of the line A O C of Fig. 1.

The figures show the principal parts of 30 my said rotary percussion implement; 20 is a cylindrical casing provided with bearings 21 and 22 in which is rotatable the actuating element 23 mounted on a high speed shaft.

The ends of the actuating element 23 have 35 the form of cylindrical sleeves in which are disposed the impact bodies 25 which have for instance a spherical form.

As in the known devices, the casing 20 has mounted therein the tool holder 26 adapted to hold the tool (not shown) which 40 operates upon the work.

Within the casing 20 is mounted, for instance by the screws 27, a cam 28 whose internal profile determines the trajectory of the bodies 25, so that each of the latter, as 45 the actuating element rotates, is first driven towards the axis of rotation and is then suddenly released, so that by the centrifugal action set up, it will be caused to strike against the head of the tool holder 26 with 50 great force.

In my invention, the internal outline of 55 the cam 28 is such that the trajectory of the bodies 25 is symmetrical relatively to the axis of rotation of the actuating element 23.

Let O be the point representing this axis

on the plane of Fig. 1; considering the line A O C passing through the two points of the outline nearest the point O, and the line D O B passing through the two points of the said outline farthest from the point O, the symmetry of the two parts of the cam 28, which are comprised in the angles A O D and B O C, is exact.

When the impact bodies pass through the angle A O B, they leave the cam 28 and strike the tool holder 26, thus describing a trajectory which depends upon their weight and their speed of rotation. The outline of the part of the cam 28 in the angle C O D is so designed as to be symmetrical with the above-mentioned trajectory.

In the portion which is diametrically opposite the tool holder 26, the different outlines are joined by rounded parts, so that there will be no prejudicial shocks.

It will be readily understood that during the operation of the implement, the trajectory of one impact body is exactly symmetrical with the trajectory of the other body, except for the very limited part corresponding to the tool holder 26, so that the centre of gravity of the aggregate of the elements 23-25 will always remain upon the axis of rotation of the element 23, and hence the system will be balanced at all times.

The reactions upon the operator will thus be reduced to the minimum, and the implement can be handled with great facility.

Obviously, my said invention is not limited to the form of construction hereinbefore described, and in particular, I may employ any suitable number of pairs of impact bodies.

I claim as my invention:

1. A rotary percussion implement, comprising, in combination, a casing; a tool holder mounted therein, a rotary actuating element disposed in said casing; a pair of impact bodies carried by said element and arranged diametrically opposite each other; and a cam within said casing to guide said bodies and permit them to strike the holder during their rotation with the actuating element, said cam imparting to both bodies simultaneously movements which are virtually symmetrical with relation to the axis of rotation of said actuating element.

2. A rotary percussion implement, according to claim 1, in which the cam is of annular form and has a peripheral surface such that any two diametrically-opposite points

throughout the greater portion of said surface are symmetrical with relation to the axis of rotation of the actuating element.

3. A rotary percussion implement, comprising, in combination, a casing; a tool holder mounted therein; a rotary actuating element disposed in said casing and having ends in the form of cylindrical sleeves; spherical impact bodies disposed in said sleeves; and a cam within said casing to guide said bodies and permit them to strike the holder during their rotation with the actuating element.

4. A rotary percussion implement, comprising, in combination, a casing; a tool holder mounted therein; a rotary actuating

element disposed in said casing and having ends in the form of cylindrical sleeves; spherical impact bodies disposed in said sleeves; and an annular cam within said casing to guide said bodies and permit them to strike the holder during their rotation with the actuating element, said cam having a peripheral surface such that any two diametrically-opposite points throughout the greater portion of said surface are symmetrical with relation to the axis of rotation of the actuating element.

In testimony whereof I affix my signature.

GEORGES ERNEST WAGNER. [L. S.]
